DEVICE FOR CONTINUOUS SPINNING
AND/OR TWISTING OF TEXTILE
FIBERSOtto George Johan Strijcken de Roysancour,
Breda, NetherlandsApplication August 6, 1932, Serial No. 627,697
In the Netherlands August 19, 1931

7 Claims. (Cl. 118—49)

My invention relates to improvements in the devices for continuous spinning and/or twisting of raw textile fibers, staples of cotton and the like, and of artificial silk.

As it is well known, in the spinning of raw fibers or staples, use is made of flyer-ring-and-cap frames, etc. Those frames however present important drawbacks due to their complicated construction, the heavy stresses to which the threads are generally subjected at high speeds of rotation, and the variations of this tension during spinning.

In the artificial silk industry, when use is made of pot spinning frames, there is a great consumption of power; moreover there is danger of the thread being injured during the further treatment; when use is made of bobbin spinning frames, the inconvenience is that the thread must be twisted afterwards.

My invention has for its object to obviate those drawbacks by simple and economical means.

With this object in view my invention essentially consists in the special arrangements and combinations of parts hereinafter fully described and pointed out in the appended claims.

In the annexed drawing:

Fig. 1 is a side view of a winding member, illustrating the principle on which my invention is based;

Figs. 2 to 4 are vertical sectional views, showing three modified embodiments of the invention for the spinning of threads of any kind whatever;

Fig. 5 is a view similar to Figs. 2 to 4, illustrating a further modification adapted to be used more especially for the spinning of artificial silk.

As is well known, in cap and ring spinning frames, the thread forms a so-called "balloon" produced by the action of centrifugal force on the thread being spun, and this balloon tends to displace itself, if not kept in place, towards the guide eye through which the thread normally passes.

The new system of spinning has been based on these two considerations. The problem consists in devising means whereby the thread can be wound under a certain tension, at the same time enabling a displacement along the spool in an axial direction of the yarn being wound (traverse motion).

Referring to Fig. 1, which shows by reference 1 a winding member for the yarn, by reference 2 a guide eye, and, in dotted lines, by reference 3 the thread forming a so-called balloon 4, the problem has been solved by "pressing down" the balloon to form what I have termed herein a

"tail" 4 by means of a member 5, for instance a cylinder, cone or other body of an appropriate shape having an inside diameter smaller than the maximum diameter of the balloon.

When spinning, the friction of the yarn against the cylinder causes it to be wound on the spool, traverse motion being obtained by moving said cylinder or other member up and down, the "tail" 4' of the balloon (part going from spool to the largest diameter of pressed down balloon) following this movement. The necessary tension is derived from the centrifugal force acting on the tail.

In the example shown in Fig. 2, 6 is a rotating bobbin on which a thread for instance of artificial silk is to be wound. 7 is a cap which surrounds the thread presented to the bobbin and also the portion of the bobbin on which the yarn is to be wound.

Under the action of the rotation of the bobbin 20 and of the resulting centrifugal force, the thread takes the shape of a balloon and is thrown against the inner wall of the cap 7, which exerts a braking action on the yarn. The feed proceeding in a continuous manner, the yarn is adapted 25 to be wound on the bobbin, the necessary tension to this end being produced by the centrifugal action consequent to the rotation of the bobbin.

The cap 7 and the bobbin 6 are mounted so as to be adapted to be displaced relatively to each 30 other in an axial direction so as to cause the thread to be wound in regular layers, and to render possible the removal of the filled bobbins from their working position and to substitute empty bobbins.

In the form of embodiment shown in Figure 3, the cap 7 is replaced by a cylindrical member 8 also exerting a braking action on the yarn and guiding it by its lower edge.

The yarn adducted to the cylinder 8 is guided 40 by means of an ordinary thread guide or lappet 9 fixed to the frame of the machine, and the form of the balloon is adapted to be controlled by varying the distance between the said guide and the bobbin or winding element 6.

Preferably, the thread guide is arranged however at a short distance above the said bobbin.

The cylindrical member can also be provided at its lower part with a conical portion 10 (Figure 4) or with a projecting ridge 11 (Figure 5).

As shown in Fig. 4, the up and down motion can be produced by a special member, for instance a ring like member 12 adapted to be moved up and down between the member 8—10 and the bobbin 6.

In Fig. 5, 13 designates a thread guiding member, used more especially for the spinning of artificial silk.

Obviously, my invention is not restricted to the specific construction as described but it must be understood that this construction can be modified in various ways without departing from the principles of the invention.

I claim:

10. 1. In a device for the purpose described, the combination with a revolving member on which thread is to be wound, and a guide for the thread axially aligned above the revolving member; of only and exclusively a single hollow member 15 forming an unbroken annular guide arranged to move up and down over the revolving member, said hollow member being open at both ends to permit passage of the thread therethrough, said hollow member being arranged to engage and 20 force inwardly toward the axis of rotation of the revolving member the upper part of the balloon normally formed by the thread during winding and to leave the lower part of such balloon substantially free for outward expansion, the said 25 hollow member and revolving member being vertically traversable one with respect to the other.
2. In a device for the purpose described, the combination with a revolving member on which thread is to be wound, and a guide for the thread axially aligned above the revolving member; of a hollow member arranged to move up and down over the revolving member, said hollow member being open at both ends to permit passage of the thread therethrough, said hollow member having 30 a relatively contracted upper portion to confine the upper part of the balloon formed by the thread and a relatively widely expanded lower portion to permit expansion of the lower portion of the balloon, said hollow member and revolving 35 member being vertically traversable one with respect to the other.
3. In a device for the purpose described, the combination with a revolving member on which thread is to be wound, and a guide for the thread axially aligned above the revolving member; of a hollow member arranged to move up and down over the revolving member, said hollow member being open at both ends to permit passage of the thread therethrough, said hollow member having 40 a relatively contracted upper portion to confine the upper part of the balloon formed by the thread and a relatively widely expanded lower portion to permit expansion of the lower portion of the balloon, having a cylindrical upper portion and an outwardly flared lower portion extending downwardly from the upper portion and provided with an inturned flange at its lower edge, said hollow member and revolving member being vertically traversable one with respect to the other.
4. In a device for the purpose described, the combination with a revolving member on which thread is to be wound, and a guide for the thread axially aligned above the revolving member; of a hollow member arranged to move up and down over the revolving member, said hollow member being open at both ends to permit passage of the thread therethrough, said hollow member having

a relatively contracted upper portion to confine the upper part of the balloon formed by the thread and a relatively widely expanded lower portion to permit expansion of the lower portion of the balloon, having a contracted neck adjacent its upper end and an outwardly and downwardly curved side wall extending downwardly from the neck and provided at its lower edge with an inturned flange, said hollow member and revolving member being traversable vertically one with respect to the other.

5. In a device for the purpose described, the combination with a revolving member on which thread is to be wound, and a guide for the thread axially aligned above the revolving member; of a hollow member arranged to move up and down over the revolving member, said hollow member being open at both ends to permit passage of the thread therethrough, said hollow member having a relatively contracted upper portion to confine the upper part of the balloon formed by the thread and a relatively widely expanded lower portion to permit expansion of the lower portion of the balloon, having a cylindrical upper portion and a frusto-conical lower portion, said hollow member and revolving member being vertically traversable one with respect to the other.

6. In a device for the purpose described, the combination with a revolving member on which thread is to be wound, and a guide for the thread axially aligned above the revolving member; of a hollow member arranged to move up and down over the revolving member, said hollow member being open at both ends to permit passage of the thread therethrough, said hollow member having a relatively contracted upper portion to confine the upper part of the balloon formed by the thread and a relatively widely expanded lower portion to permit expansion of the lower portion of the balloon, having a cylindrical upper portion and an outwardly flared lower portion extending downwardly from the upper portion and provided with an inturned flange at its lower edge, said hollow member and revolving member being vertically traversable one with respect to the other.

7. In a device for the purpose described, the combination with a revolving member on which thread is to be wound and an unbroken annular guide for the thread axially aligned above the revolving member, said annular guide consisting of only and exclusively one unbroken hollow member arranged to move up and down over the revolving member, said hollow member being open at both ends to permit passage of the thread therethrough, the balloon produced by the centrifugal force on the thread being free for outward expansion at the lower part of said hollow member and the latter exerting a tangential braking action on the said balloon whilst guiding it during its winding, the said hollow member and revolving members being vertically traversable one with respect to the other.
